(57) **CLAIM**

The ornamental design for a purse with latch, as shown and described.

DESCRIPTION

FIG. 1 is a perspective view of a purse with latch showing my new design;

FIG. 2 is a front elevational view thereof;

FIG. 3 is a side elevational view thereof with the opposite side being a mirror image;

FIG. 4 is a fragmented side view showing a closed latch;

FIG. 5 is a fragmented side view showing the latch partially open;

FIG. 6 is a fragmented side view showing the latch shown completely unlatched;

FIG. 7 is a bottom view thereof; and,

FIG. 8 is a perspective view shown in an opened position.
